CONTAINER

Maurice E. B. Owens, Cumberland, Md.

Application November 20, 1933, Serial No. 698,913
Renewed December 11, 1935

1 Claim. (Cl. 220—1)

This invention relates to a container especially adapted for the sale of motor fuel or lubricants under seal to prevent tampering therewith or the evaporation or loss of the contents of the container, and has for the primary object the provision of a device of the above stated character which will maintain an upright position on a support and may not be opened without destruction and may be readily opened with a key and will present an efficient discharge medium whereby the contents may be dispensed without the chance of waste or loss.

With these and other objects in view this invention consists in certain novel features of construction, combination and arrangement of parts to be hereinafter more fully described and claimed.

For a complete understanding of my invention, reference is to be had to the following description and accompanying drawing, in which:

Figure 1 is a side elevation illustrating a container constructed in accordance with my invention.

Figure 2 is a similar view showing an opposite side of the container.

Figure 3 is a fragmentary vertical sectional view illustrating the key positioned ready to open the container.

Figure 4 is a fragmentary sectional view illustrating the container after being opened and positioned for the dispensing of the contents of said container.

Referring in detail to the drawing, the numeral 1 indicates a container preferably of substantially conical shape so as to present to the container a bottom or base of considerable size capa-

ble of maintaining the container in an upright position on a support. The apex of the container is cut away to form a mouth adapted to be closed after the filling of the container with a motor fuel or lubricant by a cap 2, the flanges of which are soldered or otherwise sealed to the walls of the container. The container is cut diagonally when forming the mouth so that one side of the container is of a greater height than the opposite side and thereby provide to the mouth a pouring lip.

The cap 2 is formed with a tongue 4 adapted to be inserted in the slot of a key 5 so that upon rotating the key 5 the cap 2 will be removed from the container so that the contents may be readily poured therefrom, as shown in Figure 4. It is to be understood that the key 5 accompanies the container by being removably secured to the wall of the container, as shown in the drawing.

Having described the invention, I claim:

A container for sealing and the dispensing of liquid to an engine comprising a conical-shaped body providing to the latter a base capable of maintaining the body in an upright position on a support, said body formed with a mouth at the end of said body opposite to the base with the mouth disposed on an inclination so that a wall of the body will provide to the mouth a pouring lip, a cap sealed to the body for closing the mouth, and a tongue formed on the cap and projecting beyond one edge thereof to be engaged by a key normally supported by the container for destroying the cap and thereby permitting the content of the body to be poured from the latter.

MAURICE E. B. OWENS.
